UNITED STATES PATENT OFFICE.

IVAN E. WEISER AND SAMUEL E. WEISER, OF TAMPA, FLORIDA.

HAIR CLOTH.

Application filed August 19, 1926. Serial No. 130,293.

The present invention relates to hair cloth for use by barbers in covering the clothes of persons whose hair is being cut.

The objects of our invention, generally speaking, are to provide a novel, simple and economical construction of hair cloth by which the use of a button, pins or other such fasteners used for securing the hair cloth about the neck of the wearer, may be avoided thereby avoiding among other disadvantages, that of the weakening of the goods of which the hair cloth is made, at the neck portion thereof; and to provide a structure which shall be entirely durable, laundered easily and without danger of impairment, be adapted to be fitted snugly about the neck of the wearer, whether large or small, and when positioned for use be highly effective in preventing the cut hair from getting in between the hair cloth and the neck of the wearer; to provide against the undue weakening of the hair cloth at the portion thereof which goes around the neck of the wearer.

With the above and numerous other objects in view as will appear as the description proceeds, the invention resides in certain details of construction as will be hereinafter more fully described and claimed.

In the drawing:

Figure 1 is a plan view of the hair cloth embodying the features of our invention,

Figure 2 is a perspective view thereof.

The hair cloth may be manufactured of any suitable material and is preferably rectangular in formation as clearly illustrated in Fig. 1 although this is not essential. The body of the hair cloth is indicated by the numeral 5 and is cut with a central circular opening 6 and with a slit 7 leading radially from the opening 6 perpendicular to one side. The four peripheral edges, the sides of the slit and the edge of the opening 6 are reinforced by being bound with bias-fold tape indicated by the numerals 8, 9 and 10 at the peripheral edges, sides of the slit, and edge of the circular opening respectively. A reinforcing strip 11 is sewed to the body 7 in a circle concentric with the opening 6 and of larger diameter so as to be spaced from the tape 10. An arcuate strip of cloth 12 is sewed to the reinforcing strip 11 and the tape 10 to be disposed therebetween for a predetermined distance a little more than

one half. A very small strip of cloth 14 is likewise sewed in spaced relation to the adjacent end of the strip 12. An elastic tape 16 is trained between the cloth 5 and the strip 12 and at one end is provided with a suitable buckle 17. The elastic tape is inserted through the band or spacing formed by the strip 12 so as to bring the buckle adjacent the strip 14. The hair cloth is now placed on the patron. One side of the neck band is placed around the back of the patron's neck and the other side of the neck band is lapped thereover. The free end of the lapped tape is inserted through the loop formed by the strip 14 and then engaged with the buckle and drawn up to the desired tension.

With this improved apron it will be seen that the opening or neck band of the hair cloth can be easily and quickly folded to conform with the lines of the neck. On the conception of the neck band used in combination with the elastic tape, the cloth absolutely prevents the hair from going down the patron's back, thus protecting the patron from the annoyance resulting from the use of the ordinary hair cloth. The hair cloth is adjustable to any size of neck without removing or replacing any of its parts. The facing or band 12 which holds the tape, reinforces the neck band at the place most needed and the elastic tape provides the method for instantly adjusting the neck band to the desired tension around the patron's neck thus keeping it snug and tight without interfering in any way with the muscles of the throat or neck. There are no metal parts, pins or buttons or the like to be fastened to the hair cloth. By removing the elastic tape from the neck band, the hair cloth is left in a condition which requires no extra trouble or expense in laundering.

It is thought that the construction, advantages, and utility of this invention will now be apparent to those skilled in this art and further detailed description is therefore deemed unnecessary. The present embodiment of the invention has been disclosed in detail since in actual practice it attains the features of advantage enumerated as desirable in the statement of the invention in the above description. We do not wish it to be understood as intending to limit this invention to the example shown as the same

may be variously modified and altered without departing from the spirit of our invention.

Having thus described our invention what we claim as new is:

1. A barber's cloth of the class described, including a body having a central opening with a slit leading therefrom radially through one side of the body, a facing sewed 10 to the body concentric about a portion of the opening, an elastic tape receivable in the facing, a bias tape sewed to the edge of the opening, the sides of the slit, and the peripheral edges of the body, a reinforcing strip disposed about the facing and opening concentric with the latter.
- 15 2. A barber's cloth of the class described,

including a body having a central opening with a slit leading therefrom radially through one side of the body, a facing sewed 20 to the body concentric about a portion of the opening, an elastic tape receivable in the facing, a bias tape sewed to the edge of the opening, the sides of the slit, and the peripheral edges of the body, a reinforcing 25 strip disposed about the facing and opening concentric with the latter, a strip disposed between the reinforcing tape of the opening and the reinforcing member last mentioned adjacent one end of the facing. 30

In testimony whereof we affix our signatures.

IVAN E. WEISER.
SAMUEL E. WEISER.
